UNITED STATES PATENT OFFICE

LEE F. CHANEY, OF SPRINGFIELD, OHIO

APPARATUS FOR FLATTENING BULBS OF THERMOMETER TUBES

Application filed January 8, 1929. Serial No. 331,130.

This invention relates to apparatus for flattening the bulbs of thermometers.

An object of the invention is to provide a simple, efficient, and inexpensive device for producing flat-bulb thermometers.

A further and more specific object of the invention is to provide an arrangement in which the hammer for flattening the bulbs is operated pneumatically and a single control valve is employed to simultaneously supply air to the hammer cylinder and to the bulbs while being flattened.

Other objects and advantages will appear from the following description and claims.

15 In the accompanying drawing:

Fig. 1 is a top plan view of the improved apparatus.

Fig. 2 is a side elevation of that portion of the apparatus in which the bulb is flattened.

20 Fig. 3 is a partial front elevation of the flattening apparatus.

Fig. 4 is an enlarged fragmentary elevation of portions shown in Fig. 2, but with some of the parts in a different working position.

Fig. 5 is an enlarged vertical section on the line 5—5 of Fig. 1.

Fig. 6 is an enlarged perspective view of a typical thermometer tube, at one stage of the manufacturing process.

Fig. 7 is an end elevation of a thermometer tube in a succeeding stage of the process of manufacture.

Fig. 8 is a partial side elevation of the flattening apparatus, looking at the side opposite that shown in Fig. 2.

Referring to the drawing, 1 represents a flat metallic angularly shaped lever pivotally connected to a standard 2, which in turn is adjustably secured to a supporting base 3, which in turn is mounted upon a suitable table (not shown). At 4 the base is provided with an inclined anvil face, which cooperates with the end of the arm 1' of the lever 1, and both the face 4 and the end of the arm are equipped with suitable heat-insulating materials, such as mica strips, 5 being that mica strip secured to the end 1' by means of metal clamping members 6 and 7, and 8 being the mica secured in place on the face 4 by the

clamping members 9 and 10, the purpose of the heat-insulation appearing at a later point in the description.

The arm 1' of the lever is in effect a hammer, and to actuate the hammer, I provide a fluid-pressure cylinder 11 formed by a vertical bore in the rear portion of the base 1, and in which is fitted a piston 12 having a piston rod 13 which passes through the upper end of the cylinder. The lower end of the cylinder is plugged as at 14, and air under slight pressure is conveyed to the cylinder by means of the hose 15, and through the connector 16 to the ports 17, and on admission of compressed air to the lower side of the piston 12, it rises and strikes the arm 1'' of the lever which is directly in the path of the piston rod, causing the end of the hammer arm 1' to descend towards the anvil face. The upward travel of the piston is limited by a stop 18 adjustably secured to a standard 19 inserted in the body 3, and by suitable regulation of the stop 18, and also by suitable adjustment of the standard 2, the face of the hammer is stopped any desired distance from the face of the anvil, the inclinations of the arm and anvil being such that they will at this point be parallel to each other. The standard 2 is adjustably mounted on the base 1 by a cap screw 20' which passes through a slotted opening 20 in the standard. A spring 21 is employed to effect a ready return of the piston 12 to the lower position, while a light spring 22 serves to retain the hammer in its raised position, as shown in Fig. 2.

It will be understood that the bulbs are blown at one end of the glass thermometer tubes, T representing the tube with its bore b, the cross-section shown in Figs. 6 and 7 being that of a typical prevailing type of tube, the advantages being that the edge E acts as a magnifier to facilitate observation. As the scale of graduations S should be placed behind the tube opposite the edge E, it is obvious that the round bulb, such as is shown in Fig. 6 will not stand parallel to the scale through its entire length unless a depression is made to receive it. Accordingly the flat bulb came into use, and as shown in Fig. 7,

the short axis of the bulb B' is in alignment with the edge E and the bore b.

The tube to be blown is inserted in the end of a hose 23, the other end of which is connected to a T 24, one of its branches connected to the hose 15 and the other to a valve mechanism V, the parts and functions of which will be explained.

The valve body is represented by 25, and is provided at its lower end with an interiorly threaded extension 26 in which is screwed a pipe 27 connected to any suitable source of compressed air supply. A ball 28 is held against a seat in a bore 28' by a spring 29, which is retained by a cross pin 30, and limits or shuts off entirely the flow of air through the remainder of the valve. An orifice 31 is provided and communicating with it is another orifice 32 leading to a connector 33 and thence to the hose 23.

An upward extension 34 has inserted therein a length of pipe 35, in the bore of which is a rod 36, having a reduced-diameter extension 37 resting on the ball 28. Pressure on the rod 36 forces the ball from its seat and allows air to flow into the orifice 31, the air stream dividing, a portion flowing into the hose 23 and 15 and the remainder flowing upwardly through the pipe 35. It should be seen from this that the quantity flowing into the hose 23 may be varied by partially closing the end of the pipe 35 while at the same time the ball 28 is being held from its seat, which is in fact the method of operation; that is, the operator places the end of a finger over the open end of the pipe 35, and by slight rocking downward pressure, the finger is made to contact the end of the rod 36 and at the same time to constrict the flow of air from the end of the pipe 35.

After inserting the tube T in the hose 23 and holding the opposite end in a flame (not shown) fusion takes place, when the operator, by manipulating the rod 36 and partially constricting the flow from pipe 35, as previously explained, causes the heated end of the tube to expand into the round bulb shape seen in Fig. 6. A gage 39 having openings 40 of different sizes is provided, it being adjusted to present to the front the size intended, and by continuing the blowing operation with the expanding bulb adjacent the desired opening the operator may observe and limit further expansion by removing the finger closure to a greater degree.

The operator then places the fused end of the tube on the anvil and in order to correctly position the same thereon there is provided a rest formed by a recess 41' in the forward edge of a plate 41, which is secured to the side of the base by a strap 41', and also a gage 42 consisting of a plate preferably of mica which is secured to the base adjacent the anvil; the under side of the mica plate acting as a gage arranged perpendicular to the face

of the anvil and substantially in line with the recess 41'. When the tube is inserted it is turned so that the edge E faces the operator, with the convex portion thereof resting in the rounded recess. In order that the tube may be accurately positioned, there is also attached to the hammer arm another gage member 43, which is formed of a flat strip of spring steel and has a downwardly projecting extension 44 in which is a V-notch 45 which engages the V-shaped portion of the tube so as to rotate the tube if necessary to correctly position it. This strip also has a slotted opening 43' to better observe the positioning of the bulb of the tube on the anvil in a cross-wise direction. The extension 44 of the hammer gage is of such length and arrangement as to contact the tube T before the hammer strikes the bulb and the pressure of this gage upon the tube is sufficient to insure the tube being held in proper position so that the bulb as finally formed will be in proper relation to the edge E of the tube. To operate the hammer after the tube has been inserted, the operator merely closes the end of the tube 35 with his finger so as to create a pressure of air sufficient to operate the piston in the cylinder; it being understood that in the act of blowing the bulb the operator does not completely close the upper end of the tube 35 thus permitting some of the air to escape therethrough and give a sufficient pressure only for the purpose of blowing the bulb. When the tube 35, however, is closed to operate the hammer, the bulb will be subjected to a momentary increase of pressure, which is advisable to prevent collapsing of the bulb by the impact of the hammer and to assist in preserving the symmetrical appearance: this increased pressure being resisted by the bulb due to the fact that the bulb has cooled to some degree after it is removed from the fusing flame. By the use of the mica strips on the hammer and anvil the cracking of the tubes from a too sudden change in temperature is obviated, since the mica, being a non-conductor of heat, prevents sudden dissipation of the heat of the bulb as would be the case if the bulb was subjected to the action of metallic surfaces during the operation of flattening. The non-heat conducting character of these mica faces also prevents dishing of the sides of the bulb which would likely occur with metallic surfaces due to the fact that the metallic surfaces would first strike and chill diametrically opposite points of the bulb and that these chilled portions of the bulb would have a tendency to press in or dish during the flattening operation.

Having thus described my invention, I claim:

1. In an apparatus of the character described, a fixed anvil, a movable hammer cooperating with said anvil, means for operating said hammer, and faces of non heat-con-

- ducting material for said hammer and anvil.
2. In an apparatus of the character described, an anvil, a movable hammer cooperating with said anvil, means for operating said hammer, and cooperating mica faces secured to the anvil and hammer.
3. In an apparatus of the character described, a fixed anvil, a movable hammer cooperating with said anvil, means for operating said hammer, a fixed gage for thermometer tubes adjacent said anvil, and a movable gage for said tube controlled by said hammer, the engaging portion of said movable gage conforming to the shape of said tube.
4. In an apparatus of the character described, a fixed anvil, a movable hammer cooperating with said anvil, means for operating said hammer, a fixed gage for thermometer tubes adjacent said anvil, and a movable gage for said tube controlled by said hammer, said movable gage having a V-shaped portion to cooperate with a V-shaped portion of said tube.
5. In an apparatus of the character described, a base having an inclined anvil face, a movable hammer cooperating with said anvil, together with means for operating said hammer, a gage member fixed to said base having an edge extended at right angles to the face of said anvil, a rest for thermometer tubes also carried by said base substantially in line with said fixed gage, and a second gage carried by said hammer adapted to engage a thermometer tube positioned on said anvil, fixed gage and rest, said movable gage having a part conforming to the shape of the tube.
6. In an apparatus of the character described, a fixed anvil, a movable hammer cooperating with said anvil, means for operating said hammer, a fixed gage for thermometer tubes adjacent said anvil, and a yieldable gage carried by said hammer having a portion conforming to the shape of said tube.
7. In an apparatus of the character described, an anvil, a movable hammer cooperating with said anvil, a fluid pressure connection for thermometer tubes, a fluid pressure cylinder for operating said hammer having a fluid pressure connection, and a common controlling device for the fluid pressure source for both of said connections.
8. In an apparatus of the character described, an anvil, a movable hammer cooperating with said anvil, a fluid pressure cylinder for operating said hammer, a connection from a fluid pressure source to said cylinder, a fluid pressure connection for thermometer tubes, a valve chamber, a valve therein for controlling both of said connections, an operating device for said valve under the control of the operator, and an air relief outlet communicating with said valve chamber also under the control of the operator.
9. In an apparatus of the character described, an anvil, a movable hammer cooperating with said anvil, a fluid pressure cylinder for operating said hammer, a connection from a fluid pressure source to said cylinder, a fluid pressure connection for thermometer tubes, a valve chamber between the source of supply and said connections, a normally closed valve therein for controlling both of said connections, an open ended tube communicating with said valve chamber, and a rod in said tube operatively associated with said valve.

In testimony whereof, I have hereunto set my hand this 5th day of January, 1929.

LEE F. CHANEY.
